UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

KEYBOARD MECHANISM.

952,584.

Specification of Letters Patent. Patented Mar. 22, 1910.

Application filed January 4, 1909. Serial No. 470,557.

To all whom it may concern:

Be it known that I, JOHN R. ROGERS, of borough of Brooklyn, county of Kings, and State of New York, have invented a new and useful Improvement in Keyboard Mechanisms, of which the following is a specification.

This invention relates to what are commonly known in the art as keyboard mechanisms, which are used to actuate the escapements for releasing from their magazines or holders the matrices in line-casting machines and the type in type composing machines.

15 It is intended more particularly for use in line-casting machines of the general organization represented in the Mergenthaler United States Patent No. 436,532, commonly known in the art under the trademark 20 "Linotype", but it is applicable to all other machines of the same general character. In these mechanisms a series of finger-keys serve to momentarily connect the parts which actuate the escapements or releasing 25 devices with a continuously rotating roll common to the series, the roll serving, through the intermediate parts, to actuate the escapements and to complete their action after the release of the keys.

30 The object of the present invention is to do away with a number of the parts which are commonly used in these mechanisms, and thus reduce their cost, while at the same time improving their action.

35 In the drawings: Figure 1 is a vertical cross-section through my mechanism with the parts in normal position, or in a position of rest. Fig. 2 is a similar view showing the parts in action. Fig. 3 is a diagram 40 illustrating the manner in which connections are commonly made from the keyboard to the escapement.

Referring to the drawings, A represents one of a series of vertically-guided reeds 45 designed to actuate an escapement or releasing device.

B represents an eccentric mounted to turn on a horizontal pivot, b, carried by an arm, a, extending edgewise from the reed, 50 A, so that the reed and the cam rise and fall together. This cam has its periphery concentric with the axis for about one half of its length and eccentric thereto for the remainder of its length. The cam is heavier 55 on one side of the center than on the other,

and has a tendency to gravitate from the position shown in Fig. 1 toward the position shown in Fig. 2; in other words, when released it will fall by gravity from the normal position to a position in which it 60 engages the driving roll. It is preferably made of the form shown in the drawing but may be widely modified, provided only that it is adapted to operate in the manner hereinafter explained. The peripheral surface 65 may be toothed as shown, or, if preferred, may be left plain.

C represents a helical spring having its upper end attached to the frame or other stationary member of the machine, and its 70 lower end connected to pin, b', on the side of the cam, the arrangement being such that when the reed descends to its normal or inactive position, shown in Fig. 1, carrying with it the cam, the spring will limit the 75 descent of the pin b' and thus hold the cam in the position shown in Fig. 1, with its shortest diameter on the under side.

D represents a horizontal, continuously rotating roll, extending transversely of the 80 keyboard, beneath the entire series of cams, B, as usual in mechanisms of this class.

E represents a finger key, mounted midway of its length on a pivot, e, and acting at its rear end upon a shoulder on the reed 85 A for the purpose of lifting the same. When the forward end of the key is depressed its rear end lifts the reed A and the cam B carried thereby. During this preliminary rising movement of the cam the 90 pin b' remains at rest while the pivot b is lifted with relation thereto. This permits the cam to turn around the pivot b, its longer and heavier side descending until it engages frictionally with the upper surface 95 of the roll D. The roll, turning in the direction indicated by the arrow, and engaged with the cam, causes the latter to turn in the direction indicated. As the cam continues to rotate it is forced bodily upward 100 and its pivot b lifted so that it in turn lifts the reed A, causing the latter to actuate the escapement. During this movement the spring C is extended somewhat as shown in Fig. 2 and the pin b' is carried with the 105 cam beneath the pivot b to such a position that after the extreme outward point of the cam passes the roll D, and when the reed A, relieved from support, descends, the spring will cause the cam to assume its 110

original position; with its lower edge out of contact with the roll. It will be observed that the spring serves the double purpose of holding the cam in the position of rest and out of contact with the driving roll, and that it also serves, after the pin b' has passed the center, to continue the motion of the cam to its original position. The spring C may be replaced by a link or any elastic connection from the pin on the cam to the support on the frame or elsewhere, but the employment of the spring is recommended as it gives to the parts an easier and smoother action.

15 The essence of my invention lies in combining with the reed a cam movable therewith, a stationary roll for driving the cam, and a connection by which the cam is held normally out of contact with the roll.

20 In Fig. 3 I have shown on a small scale the parts above described and also the usual escapement, G, mounted on the under side of the usual matrix magazine, H, and engaged by the upper end of the reed. The reed when carried upward moves the escapement in one direction, and when the reed returns the motion of the escapement is reversed by the spring I.

Having thus described my invention,

what I claim and desire to secure by Letters Patent, is:

1. The movable reed A and the gravitating cam carried thereby, in combination with the cam driving roll, and a spring extending from a fixed support and acting on the cam to sustain the same normally out of engagement with the roll.

2. In a keyboard mechanism and in combination, a reciprocating reed, a rotary, gravitating cam carried thereby, the cam driving roll, means for holding the cam upward normally out of engagement with the roll, and a manual device acting on the reed to initiate its movement.

3. In a mechanism of the class described, and in combination with the underlying roll, D, a vertically movable cam and a spring tending primarily to hold the cam out of contact with the roll, and secondarily to continue the rotation of the cam as the roll concludes its action thereon.

In testimony whereof I hereunto set my hand this thirtieth day of December, 1908, in the presence of two attesting witnesses.

JOHN R. ROGERS.
